UNITED STATES PATENT OFFICE

94,796

DESIGN FOR A SHOE

Curt Wolfelt, New York, N. Y.

Application December 22, 1934, Serial No. 54,536

Term of patent 3½ years

To all whom it may concern:

Be it known that I, Curt Wolfelt, a citizen of the United States, and resident of New York city, in the county of New York and State of New York, have invented a new, original, and ornamental Design for a Shoe, of which the following is a specification, reference being had to the accompanying drawing forming part thereof, in which,

Fig. 1 is a plan view of a shoe showing my new design, and

Fig. 2 is a side perspective view of the shoe shown in Fig. 1.

I claim:

The ornamental design for a shoe as shown.

Dated, November 25, 1934.

CURT WOLFELT.
